UNITED STATES PATENT OFFICE.

EDWARD T. CONDON, JR., OF NEW YORK, N. Y., ASSIGNOR TO CONDON-AUTOSTOP COMPANY, A CORPORATION OF NEW YORK.

AUTOMATIC BRAKE MECHANISM.

1,186,969.

Specification of Letters Patent. Patented June 13, 1916.

Application filed January 18, 1913. Serial No. 742,762.

To all whom it may concern:

Be it known that I, EDWARD T. CONDON, Jr., a citizen of the United States, residing in the city of New York, in the county and 5 State of New York, have invented certain new and useful Improvements in Automatic Brake Mechanism, of which the following is a specification.

My present invention relates to automatic 10 brake mechanism designed particularly for use in connection with talking machines of the type in which a rotary disk record is employed, although it may be found useful in other and different connections.

15 The object of the invention is to provide a brake mechanism which is simple and inexpensive and can readily be attached to any standard talking machine of the rotary disk type and which, without adjustment or 20 regulation, will automatically apply the brake and stop the machine when the end of a selection is reached, notwithstanding variations in the pitch of the sound-groove of the record used and no matter how long 25 or how short the selection may be.

To this end the invention consists, broadly stated, in a brake member which is supported by and travels with one moving member, such as the sound-arm of a talking machine, 30 and is normally held in inoperative position, and in means actuated on the stopping of such moving member for bringing the brake into operative position in contact with another moving member, the revolving turn-table of the talking machine for example, to 35 stop such other member.

It also comprises the novel features of construction, arrangement, and combinations of parts hereinafter fully described and 40 more particularly pointed out in the claims.

In the accompanying drawings, forming a part of this specification, Figure 1 is a plan view of one specific embodiment of my improved brake mechanism as applied to a 45 standard talking machine, with broken portions of such parts of the machine as are necessary to show the operative relationship of the brake mechanism therewith; Fig. 2, a vertical section on the line 2 2 of 50 Fig. 1, in the direction indicated by arrows; and Fig. 3, a vertical section on the line 3 3 of Fig. 1, also in the direction indicated by 55 arrows.

The same reference numerals indicate like parts throughout the several figures of 55 the drawings.

As here shown, 1 is the usual rotary turn-table, 2 is a disk record supported thereon and revolving therewith, and 3 is the usual sound-arm which, when the machine is in 60 operation, is swung inwardly by the needle which rests in the spiral sound-groove of the record. Mounted upon the sound-arm by the strap 4 is an arm having a horizontal component 5 which extends forwardly under the sound-arm between the top of the motor cabinet (not shown) and the turn-table. To the forward end of this arm is pivoted, at 6, the brake member 7, consisting of two arms 7^a and 7^b which extend oppositely at an angle to each other and are so proportioned that the upper side of the arm 7^a, preferably provided with a shoe or covering of rubber, or other suitable frictional material, is normally held by gravity in a 65 substantially horizontal position in proximity to but out of contact with the turn-table above while the arm 7^b, tapering to a sharp toothed edge at its outer end, projects downwardly, as shown in Fig. 2. Upon the base-plate 8, which is attached by screws or other suitable means to the top of the motor cabinet (not shown), is pivotally mounted a sprocket wheel 9, with a tooth of which a finger 10 screwed or otherwise suitably secured to the under side of the turn-table 70 engages on each revolution of the turn-table and so causes it to rotate. The pinion 11, mounted upon the same pivot as and to rotate with the sprocket wheel, meshes with 75 gear 12 which rotates with the pinion 13 upon a post 14 secured to the base-plate. A lever 15 is mounted between the gear 12 and pinion 13 to turn upon the hub 13^a on the latter, and to one of its arms is attached a 80 spring 16 while the gear 17 is pivotally mounted upon its other arm and thereby held in mesh with the pinion 13. The gear 17 is normally held by the spring 16 in mesh with the segmental rack 18, which, 85 provided on its lower side with a curved longitudinal flange 19 sliding in the segmental groove 20 in the base-plate, is positioned 90 immediately below the brake 7 and moves around the same center. The upper surface 95 of the rack is provided with fine transverse 100

ratchet teeth 21 with which the toothed outer end of the downwardly projecting arm of the brake is adapted to engage.

The gears in the train actuating the rack 5 are so proportioned that the rack will move more slowly, or at least no faster, than the brake, however high the pitch of the sound-groove of the record used may be, and the teeth on the upper surface of the rack are 10 extended so that the downwardly projecting arm of the brake will always be in engagement therewith whenever the end of a selection, whether long or short, is reached.

The operation of the device is as follows: 15 When the machine is started with the needle in the outer end of the spiral sound-groove of the record, the brake stands just off the end of the segmental rack, to the right, with its horizontally extending arm held out of 20 contact with the turn-table by gravity, in the position indicated by the dotted lines in Fig. 2. As the sound-arm is swung inwardly by the needle, the brake moving with it will drag the toothed end of its downwardly projecting arm over the ratchet teeth on the upper surface of the more slowly moving rack until the needle reaches the end of the sound-groove. Thereupon the sound-arm will cease to move, or remain stationary, and 25 the brake will be turned upon its pivot by the engagement of its downwardly projecting arm with a tooth on the still moving rack so as to bring its forwardly projecting arm up into contact with the rapidly revolving turn-table which, by reason of the frictional contact, will give a slight wedge action to the brake-arm and be instantly stopped. To release the brake and start the machine again, it is only necessary to swing 30 the sound-arm back to the right by hand. The downwardly projecting arm of the brake in engagement with a tooth on the rack will move the rack back to the right, throwing the gear 17 forward and out of 35 mesh with the rack, until the longitudinal flange on the rack strikes the end of the segmental slot in the base-plate and will then jump the small ratchet teeth to the end of the rack.

40 While I have explained the principle of my invention in connection with what I now consider the best mode in which to apply that principle, it will, of course, be understood that the specific embodiment of the invention shown and described can be greatly modified in its various parts and details, within the scope of the appended claims, without departing from the spirit or sacrificing the advantages thereof.

45 What I claim as new, and desire to secure by Letters Patent, is—

1. In a brake mechanism, the combination with two moving members of a brake which is mounted to be moved by one of said moving members and means rendered operative

by the stopping of said brake moving member to render said brake operative to stop the other moving member.

2. In a brake mechanism, the combination with two moving members of a brake for 70 one member which is mounted to move with the other member and which is adapted to be actuated to stop the member to be braked only when the speed of the member by which it is moved falls below a certain fixed 75 minimum relative to the speed of the member to be braked.

3. In a brake mechanism, the combination with two moving members of a brake for 80 one member which is mounted to move with the other member and mechanical connections between the member to be braked and the brake which are rendered operative to actuate the latter only when the member by which it is moved travels at a speed below a 85 fixed minimum relative to the speed of the member to be braked.

4. In a brake mechanism, the combination with two moving members adapted to travel 90 one at substantially constant and the other at varying speeds of a brake for said constant speed moving member mounted to move with said varying speed member and means adapted to remain inoperative during normal variations in the speed of said varying speed moving member and to be rendered operative on the stopping thereof to positively apply said brake to stop said constant speed moving member.

5. In a brake mechanism, the combination 100 with two moving members adapted to travel one at a substantially constant and the other at varying speeds of a brake member for the constant speed moving member mounted to be moved by said varying speed moving 105 member and a second member mounted to be moved by said constant speed moving member which inoperatively engages the brake member so long as said variable speed moving member is moving at a speed at or 110 above a normal minimum and on a reduction of its speed below such normal minimum is brought into operative engagement therewith to actuate the brake member.

6. In a brake mechanism, the combination 115 with two moving members adapted to travel one at a substantially constant speed and in so doing to drive the other member at varying speeds of a brake member for the constant speed moving member and means for 120 actuating the brake member which becomes operatively coupled therewith only when the varying speed moving member is traveling at a speed below a certain predetermined minimum relative to the speed of the constant speed moving member.

7. In a brake mechanism, the combination, with two independently moving members, of a brake member which is mounted to move with one moving member in close proximity 125

to but not in contact with the other moving member and means rendered operative by the stopping of the first moving member to bring the brake member into contact with the other moving member.

8. In a brake mechanism, the combination, with a traveling arm and a revolving table, of a brake member pivotally mounted upon and moving with the traveling arm and held by gravity in close proximity to but out of contact with the revolving table, means becoming operative upon the stopping of the traveling arm to turn the brake member upon its pivot so as to bring it into contact with the revolving table.
9. In a brake mechanism, the combination, with an arm traveling in one direction and a rotating table moving in the opposite direction, of a brake member pivotally mounted upon and moving with the traveling arm in proximity to the rotating table but held out of contact therewith so long as the traveling arm continues to move, and means becoming operative upon the stopping of the traveling arm to turn the brake member upon its pivot into contact with and by such contact to wedge it against the rotating table.
10. In a brake mechanism, the combination, with a traveling arm adapted to move in one direction and a rotating table moving in the opposite direction, of a brake member pivoted upon and moving with the traveling arm and provided with two arms which are held by gravity one forwardly extended in

proximity to but out of contact with the rotating table and the other downwardly and rearwardly inclined, a sliding rack positioned below the brake member and provided with ratchet teeth adapted to engage the end of its downwardly projecting arm, and means actuated by the rotating table for moving the rack in the same direction in which the traveling arm is moved but at a lower rate of speed.

11. In a brake mechanism, the combination, with a traveling arm moving normally in one direction and a rotating table moving in the opposite direction, of a brake member pivotally mounted upon and moving with the traveling arm and provided with two arms which are held by gravity one forwardly extended in proximity to but out of contact with the oppositely moving rotating table and the other downwardly and rearwardly inclined, a sliding rack positioned below the brake member and provided with ratchet teeth adapted to engage the end of its downwardly projecting arm, and means actuated by the rotating table for moving the rack in the same direction in which the traveling arm normally moves but at a lower rate of speed and adapted to disengage the rack when the traveling arm carrying with it the rack is moved in the opposite direction.

EDWARD T. CONDON, JR.
